Primary Examiner — Marianne Pandozzi*(74) Attorney, Agent, or Firm* — Knobbe Martens Olson & Bear LLP(57) **CLAIM**

The ornamental design for a beverage carbonation apparatus, as shown and described herein.

DESCRIPTION

FIG. 1 is a perspective view of a beverage carbonation apparatus showing our new design;

FIG. 2 is a front view thereof;

FIG. 3 is a rear view thereof;

FIG. 4 is a left side view thereof;

FIG. 5 is a right side view thereof;

FIG. 6 is a bottom plan view thereof; and,

FIG. 7 is a top plan view thereof.

The broken lines in the drawings are included for the purpose of illustration and form no part of the claimed design.

1 Claim, 6 Drawing Sheets(56)
